The ornamental design for a cartridge for television receiver, as shown and described.

DESCRIPTION

FIG. 1 is a perspective view of the front, top and left side of a cartridge for television receiver showing my new design; FIG. 2 is a perspective view of the rear, top and right side thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof; and,

FIG. 9 is a perspective view thereof, showing the cartridge for television receiver in its environmental use.

The elements shown in broken lines are for illustrative purposes only and form no part of the claimed design.
